(US) LLP

(73) Assignee: **Sartorius Stedim North America Inc.**,
Bohemia, NY (US)

(57) **CLAIM**

The ornamental design for an locking device for luer connection, as shown and described.

DESCRIPTION

(***) Term: **15 Years**

(21) Appl. No.: **29/739,575**

(22) Filed: **Jun. 26, 2020**

(51) LOC (13) Cl. **24-02**

(52) U.S. Cl.

USPC **D24/129**

FIG. 1 is a front, right perspective view of a locking device for luer connection, showing my new design;

FIG. 2 is a rear, right perspective view of the locking device for luer connection of FIG. 1;

FIG. 3 is a top view of the locking device for luer connection of FIG. 1;

FIG. 4 is a right side of the locking device for luer connection of FIG. 1;

FIG. 5 is a front view of the locking device for luer connection of FIG. 1;

FIG. 6 is a back view of the locking device for luer connection of FIG. 1;

FIG. 7 is a right side view of the locking device for luer connection of FIG. 1 in an environment of use; and,

FIG. 8 is an enlarged view of an indicated area of detail of FIG. 7.

The dash-dash broken lines represent the portions of the locking device for luer connection that form no part of the claimed design.

The dash-dot lines show the bounds of the claimed and form no part thereof.
